John Nutry Inventor
By his Attorney
L. S. Goodfellow

UNITED STATES PATENT OFFICE.

JOHN NUTRY, OF RIDGEWOOD, NEW JERSEY.

NOVELTY CONTAINER.

Application filed June 11, 1921. Serial No. 476,853.

To all whom it may concern:

Be it known that I, JOHN NUTRY, a citizen of the United States, residing at Ridgewood, in the county of Bergen and State of New Jersey, have invented certain new and useful Improvements in Novelty Containers, of which the following is a specification.

This invention relates to a novelty container, and an object of the invention is to provide a simple form of container having the appearance of a book.

A further and more detailed object is to provide a container made up of a sheet of suitable material folded upon itself into a U-shape, the legs of the U being spaced apart so that said legs form the front and back covers of the book, while the connecting portion of the U serves to represent the binder portion of the book, and to provide means fitted into position between the marginal portions of the cover forming parts at once representing the book leaf edges and defining an enclosure between said covers.

A further object is to provide simple and efficient means for holding in position the leaf edge forming parts.

A further object is to provide simple and efficient means whereby access may be gained into the interior of the container.

Other objects and aims of the invention, more or less specific than those referred to above, will be in part obvious and in part pointed out in the course of the following description of the elements, combinations, arrangements of parts and application of principles, constituting the invention; and the scope of protection contemplated will be indicated in the appended claims.

In the accompanying drawings which are to be taken as a part of this specification, and in which I have shown merely a preferred form of embodiment of the invention,

Figure 1 is a side elevational view of a container constructed in accordance with this invention, parts being broken away and shown in section for better disclosing the construction.

Figure 2 is a longitudinal sectional view taken substantially upon the plane of line II of Fig. 1.

Figure 3 is a fragmentary detail sectional view taken upon the plane of line III of Fig. 1.

Figure 4 is a fragmentary perspective view showing one of the fastening devices, and

Figure 5 is a top end view of the structure shown in Fig. 1.

Referring to the drawings for describing in detail the structure therein illustrated, the reference characters L and G indicate the front and back cover portions of the container, or book, said portions, as above suggested, preferably being formed from a single piece of sheet metal folded upon itself into U-shape and providing a connecting portion 1 for constituting one edge wall of the container designed to represent the binder portion of the book.

This piece of sheet metal, as thus bent, may be suitably ornamented, painted, covered or printed in any desired manner, to properly represent a book.

Any appropriate means may be employed for holding the outer end portions of the parts L and G in fixed relation, but preferably a suitable number of wire clips, as 2, is employed. These clips each consist of a single length of wire bent into U-shape and having leg portions 3 for engaging beneath struck-up portions 4 of the parts L and G, as clearly seen in Fig. 4.

Fitted into the space between the cover parts L and G, near the margins thereof, are wall members 5, 6 and 7. These wall members are made from a strip of suitable material bent into U-shape providing edge flange portions 8 projecting inwardly and resting flat against the inner surfaces of the cover portions L and G. The outer surfaces of these walls may be painted, or otherwise decorated, to represent the book leaf edges.

The wall member 5 extends longitudinally of the book, or container, and its flanges 8 are disposed to engage against the adjacent wire clip 2, as at 9, for holding said wire clip against disengagement from the struck-up portions 4 of the covers. At another point these flanges are provided with undercut grooves 10 extending longitudinally thereof arranged for engaging another of said wire clips to prevent detachment of said clip.

The wall member 6 extends longitudinally of the book, or container, and its flanges 8 are disposed to engage against the adja-

cent wire clip 2, as at 11, for holding said wire clip against displacement. The end portion of this wall adjacent to the wall 1 is formed with a tang 12 arranged for interengaging with a struck-up portion 13 of said wall 1 to hold the parts in proper assembly.

The walls 5 and 6 are connected together, as at 14, they being preferably made from a single piece of suitable material such, for instance, as thin sheet metal, and it will be noted, in this connection, that the disposition of the clips 2 and their relation to the flanges of said walls is such that engagement of the flanges of wall 6 with the adjacent wire clip, as at 11, will positively hold the undercut slots 10 of the flanges of wall 5 against possible disengagement from their clip and will not only hold the clip against displacement but the clip will in turn hold the wall 5 against displacement.

The operation of assembling these parts is also made very simple and cheap by this construction since all that is required is, first, to move the slots 10 into engagement with their wire clip, and then move the tang into engagement with the portion 13 of wall 1 and bend said tang over, as indicated. The simple act of moving the tang 12 into engagement with the portion 13 will obviously cause the flanges of wall 6 to cam along their adjacent wire clip in a manner to force the wall 5 in a direction so that the slots 10 will move tightly into engagement with their respective wire clip.

The wall 7 is preferably separately formed and is pivotally connected to wall 5 so that it constitutes a door providing means of access into the interior of the container. A suitable hinge rod 15 extending between the flange portions of the two walls serves admirably as a hinge element.

The free end of this door is arranged to engage a stop element 16 carried by the wall 5. There is also provided a lock device H, carried by the inner side of the door and having the form of a shallow, inverted trough. This member carries a pair of latch heads 17, extending laterally from it, for the purpose of engaging opposite edges of the stop 16. This lock device may be operated by a key, or like implement, inserted thru a keyhole, as 18.

A container made in this fashion, properly ornamented, and finished, makes a very attractive article and may be used in various ways for the carrying of samples, documents or other articles.

Or, as is suggested by the presence of the money slot 19 formed thru the wall 6, and the guard element 20 adjacent thereto, this container may be used as a bank and when so used a very appreciable point of advantage is noted in that it may be placed upon a book shelf in company with other books

where its identity as a container of valuables will not be apparent.

While it has been herein shown and described that the parts of this device are particularly adapted to the production of a container having the appearance of a book, nevertheless it will be understood that the invention is not to be limited in this respect since obviously the container produced may be made to represent other articles than a book. Hence, it is to be understood that wherever herein, and particularly in the claims, a book, or the essentials thereof, are referred to, such language is used merely to identify the particular portions of structure referred to.

Having thus described my invention, what I claim as new and desire to secure by Letters Patent is:—

1. A novelty container in the form of a book, comprising a single sheet of suitable material folded upon itself into U-shape to represent the front and back cover portions and a binder portion of the book, a separate member inserted between said cover portions to represent the leaf edges and to define an enclosure between said covers, a plurality of retaining clips engaging within openings provided in said covers for retaining said covers in position, each clip being made of a single piece of wire, said leaf edge forming member having a part interengaging with one of said clips to hold one portion of said leaf edge forming member in position, said leaf edge forming member having another part engaging another of said clips to hold said second clip against displacement, and said leaf edge forming member having a third part engaging a third clip for holding the first mentioned part in cooperative assembly with the first clip and for holding the third clip against displacement.

2. A novelty container in the form of a book, comprising a single sheet of suitable material folded upon itself into U-shape to represent the front and back cover portions and a binder portion of the book, a separate member inserted between said cover portions to represent the leaf edges and to define an enclosure between said covers, a plurality of clips, said front and back cover portions having pockets thereon into which portions of said clips are received to hold said cover portions connected to each other, and said leaf edge forming member being disposed to engage said clips for holding said clips in engagement with said pockets.

3. A novelty container in the form of a book, comprising a single sheet of suitable material folded upon itself into U-shape to represent the front and back cover portions and a binder portion of the book, a separate member inserted between said cover portions to represent the leaf edges and to define an enclosure between said covers, a plu-

rality of clips, said front and back cover portions having pockets thereon into which portions of said clips are received to hold said cover portions connected to each other, 5 and said leaf edge forming member being disposed to engage said clips for holding said clips in engagement with said pockets, said leaf edge forming member having a hook-like portion engaging one of said clips 10 to assist in holding said leaf edge forming member in position.

4. A novelty container in the form of a book, comprising a single sheet of suitable material folded upon itself into U-shape to 15 represent the front and back cover portions and a binder portion of the book, a separate member inserted between said cover portions to represent the leaf edges and to define an enclosure between said covers, a plu- 20 rality of clips, said front and back cover portions having pockets thereon into which portions of said clips are received to hold said cover portions connected to each other and said leaf edge forming member being dis- 25 posed to engage said clips for holding said clips in engagement with said pockets, said leaf edge forming member being connected by one of its ends to said binder portion and having at its opposite end a pocket into 30 which a portion of one of said clips is received whereby to hold said leaf edge forming member in position.

5. A novelty container in the form of a book, comprising a single sheet of suitable 35 material folded upon itself into U-shape to represent the front and back cover portions and a binder portion of the book, a separate member inserted between said cover portions to represent the leaf edges and to de- 40 fine an enclosure between said covers, and retaining means for retaining said cover portions in position comprising a U-shaped member having its opposite legs engaging within pockets provided in said cover por- 45 tions respectively and being arranged so that the connecting part of the U between the legs thereof constitutes a strut extending between said cover portions, the pockets for receiving the legs of at least one of said 50 retaining members facing outwardly toward said leaf-edge forming member and said

leaf-edge forming member standing in en- gagement with the strut portion of said mentioned retaining member to hold the legs of said mentioned retaining member within 55 their pockets.

6. A novelty container in the form of a book, comprising a single sheet of suitable material folded upon itself into U-shape to represent the front and back cover portions 60 and a binder portion of the book, a separate member inserted between said cover portions to represent the leaf edges and to de- fine an enclosure between said covers, 65 retaining means for retaining said cover portions in position comprising a U-shaped member having its opposite legs engaging within pockets provided in said cover portions respectively and being arranged so that the connecting part of the U between 70 the legs thereof constitutes a strut extend- ing between said cover portions, and said leaf edge forming member having a part disposed to engage said retaining means and to hold the legs of said retaining 75 means in position within said pockets.

7. A novelty container in the form of a book, comprising a single sheet of suitable material folded upon itself into U-shape to represent the front and back cover portions 80 and a binder portion of the book, a separate member inserted between said cover portions to represent the leaf edges and to de- fine an enclosure between said covers, a member extending between said cover por- 85 tions to hold said cover portions in position, said leaf edge forming member being connected at one point in its length to said connecting member to hold said connecting member in position and to hold the adjacent 90 portion of the leaf edge forming member in position, and said leaf edge forming mem- ber being connected at another point in its length with the binder portion so as to hold a different part of the leaf edge forming 95 member in position.

In testimony whereof I affix my signature in the presence of two witnesses.

JOHN NUTRY.
